F. P. ZALEVSKI AND L. P. HRYSHKA.

HANGER BRACKET.

APPLICATION FILED JULY 16, 1920.

1,382,709.

Patented June 28, 1921.

UNITED STATES PATENT OFFICE.

FELIX P. ZALEVSKI AND LAWRENCE P. HRYSHKA, OF PRESTON, ONTARIO, CANADA.

HANGER-BRACKET.

1,382,709.

Specification of Letters Patent. Patented June 28, 1921.

Application filed July 16, 1920. Serial No. 396,866.

To all whom it may concern:

Be it known that we, FELIX P. ZALEVSKI, a subject of the King of Great Britain, and LAWRENCE P. HRYSHKA, a citizen of Poland, residing at Preston, in the county of Waterloo and Province of Ontario, Canada, have invented certain new and useful Improvements in Hanger-Brackets, of which the following is a specification.

10 Our invention relates to improvements in brackets and more particularly to a novel device embodied in a bracket providing means for extending the article hung on the bracket to a more remote distance from the 15 wall of the building or such structure to which the bracket is secured, the invention consisting essentially of a horizontal rod supported from the structure, and having a trolley operative thereon, together with 20 novel means for altering the position of said trolley on said rod, and means for hanging an article from said trolley.

The invention has for its primary object 25 to provide suitable means in a bracket to be secured to a window sash for the purpose of hanging out articles such as clothes hangers for drying purposes and the like, whereby the position of said articles may be changed from one within reach of a person 30 standing within the building and juxtaposed to the window, to one more remote from the building so that said hanging article may not come in contact with the building owing to wind and the like.

35 We do not confine our invention, however, to the particular purpose described above; the device may be utilized for various purposes by varying the proportions thereof.

A further object is to provide a device of 40 the class specified which will be simple, durable, efficient in operation, and comparatively inexpensive to manufacture.

These, together with other objects, may be attained by the construction, combination 45 and arrangement of the parts as will be hereinafter more particularly described, illustrated in the accompanying drawing, and pointed out in the claim hereunto appended.

50 Referring to the drawing:

Figure 1 is a side elevation of the entire

improved bracket showing the trolley in full extended position in full lines, and in the opposite position in dotted lines;

Fig. 2 is an enlarged detailed reverse side 55 elevation of the actuating mechanism; and,

Fig. 3 is a top view of the bracket brace.

Similar reference characters refer to similar parts throughout the several views.

A indicates the horizontal bracket rod 60 bolted to the perpendicular member B at 2, which is in turn bolted or screwed to the window sash indicated by C. The said rod is supported by the strut D, and is rigidly retained in its proper position by the horizontal brace E, secured to the opposed sash of the window in angular relation to the said rod. The free end of the brace E is provided with a plurality of holes 3, any of which are adapted to engage the post 4 70 on the rod A. This multiplicity of holes provides means which render the device adjustable to various widths of windows.

The trolley, whose range of travel upon the rod A is between the upper termination 75 of the strut D and the stop 5 on the end of the rod, comprises a grooved sheave 6 having bearing in and supporting a sleeve 7 slidable on said rod. Attached to the bearings of said sheave is a link 8, or its equivalent, for attaching an article indicated by 9.

A connecting rod 10 is pivotally connected to the sleeve 7 at 11, and to the lever 12 at 13. The said lever is fulcrumed to the strut D at 14. A connecting rod 15 is pivotally connected to the lever 12 at 16, and to a hand lever 17 at 18. The hand lever 17 is fulcrumed to a bearing 19 at 20, integral with the perpendicular member B, and swings from an upright position to a depending position, as clearly shown in Fig. 2, thereby actuating the trolley from full extended position to full abridged position. The rod 15 is curved at 21 in order to escape the bearing 19 while changing position.

Having now fully described my invention, what I claim and desire to secure by Letters Patent is:—

In a device of the class described, a vertical member, a horizontal rod extending 100 from the vertical member, a strut secured to said vertical member and supporting said

horizontal rod, a trolley having limited travel on said rod, means on the trolley for suspending an article therefrom, a three-cornered body pivotally connected at one of its corners to said strut, a connecting rod pivotally connected to said three-cornered body at another corner thereof, and pivotally connected to said trolley, a lever fulcrumed to said vertical member, a connecting rod pivotally connected to said lever and

pivotally connected to the three-cornered body at its other corner.

In testimony whereof we have affixed our signatures.

FELIX P. ZALEVSKI.

his

LAWRENCE P. $\times$ HRYSHKA.
